UNITED STATES PATENT OFFICE.

DANIEL MCCHESSIE, OF WEBBWOOD, ONTARIO, CANADA.

TRACKWALKER'S KIT.

1,397,644.

Specification of Letters Patent.

Patented Nov. 22, 1921.

Application filed November 10, 1919. Serial No. 336,964.

To all whom it may concern:

Be it known that I, DANIEL MCCHESSIE, a subject of the King of Great Britain, a resident of the town of Webbwood, Province 5 of Ontario, Dominion of Canada, have invented certain new and useful Improvements in Trackwalkers' Kits, of which the following is a specification.

This invention relates to improvements in 10 track-walkers' kits, and the objects of the invention are to arrange the kit compactly so that it may be readily carried from place to place and adjusted to perform all the necessary functions, and to embody the kit 15 in a single tool, the several parts of which are capable of adjustment to suit the work being performed.

With the above and other objects in view the invention consists essentially of the im- 20 proved construction particularly described and set forth in the following specification and accompanying drawings forming part of the same.

In the drawings:

25 Figure 1 is a perspective view of a track walker's kit as seen in the carrying position;

Fig. 2 is a perspective view of a portion of the kit when used as a claw-hammer for removing spikes, the wrench acting as a 30 fulcrum;

Fig. 3 is a fragmentary side elevation of the kit as seen when utilized as a claw-hammer;

Fig. 4 is a plan view of the wrench por- 35 tion of the kit;

Fig. 5 is a plan view of the kit used as a track wrench;

Fig. 6 is a plan view of a portion of the kit used as a pinch-bar; and

40 Fig. 7 is a plan view of the spanner de- signed to be used to adjust the several por- tions of the kit.

Like characters of reference refer to the like parts in the several figures.

45 Referring to the drawings, A represents a track carrier's kit comprising a pinch-bar 10 having a socket 11 at one end through the walls of which the set-screw 12 extends. The end of the pinch-bar remote from the 50 socket 11 is reduced forming a tapered tip 13, and a recess 14 is located in the pinch-bar adjacent to the said tip. The bar may be used as a gage, and for this purpose is graduated as shown at 15 and 16.

55 A wrench 17 is provided having a reduced stem 18 adapted to engage with the socket

11 and be frictionally retained therein by the set-screw 12.

A claw-hammer 19 is also provided having a central orifice 20 with which the tapered tip end of the pinch-bar is designed to engage, and a set-screw 21 is threaded through the head of the claw-hammer to engage with the recess 14, so holding the claw-hammer in position.

65

One end of the claw-hammer is offset as shown at 22 and provided with a claw 23 and the opposite end 24 of the hammer head is reduced. This reduced portion 24 is of such a dimension that it could be engaged 70 by the socket 11 of the pinch-bar 10, so that the claw-hammer could be used in conjunction with the wrench 17 as a fulcrum, as shown in Fig. 3 for removing spikes. The set-screws are loosened and tightened 75 by the spanner 25.

When the device is being carried it will be assembled as shown in Fig. 1 with the claw-hammer attached to one end of the pinch-bar 10 and the wrench 17 engaging with the 80 socket 11. In this position the claw-hammer can be used for driving purposes and the wrench for tightening or loosening bolts and nuts.

Should it be found necessary to remove 85 spikes then the claw-hammer will be disengaged from the end of the pinch-bar, and the reduced portion 24 will be inserted in the socket 11, from which the wrench 17 has been removed, and the set-screw 12 will be 90 tightened to hold the claw-hammer in the desired position shown in Fig. 3.

The wrench 17 will be placed under the claw portion of the hammer and will act as a fulcrum, and the spike head will be 95 engaged by the claw 23, whereupon force will be applied to the bar 10 to draw the spike.

The pinch-bar can be used above as such, the point 13 being so formed that it can be 100 advantageously inserted into any small space for this purpose; and the bar can also be used as a gage.

From the above description it will be seen that I have invented a trackwalker's kit 105 which is of an extremely compact nature, the several parts being readily adjustable and capable of being secured in the desired position with a minimum of time and labor. By securing the several parts in this manner 110 there is no possibility of the parts becoming lost, and this kit eliminates the necessity

of carrying a kit bag with separate tools which are always liable to be mislaid.

As many changes could be made in the above constructions, and many apparently 5 widely different embodiments of my invention, within the scope of the claim, constructed without departing from the spirit or scope thereof, it is intended that all matter contained in the accompanying drawings and specification shall be interpreted 10 as illustrative and not in a limiting sense.

What I claim as my invention is:

A track-walker's kit, comprising the combination with a pinch-bar having a reduced

tip at one end and a socket at the opposite 15 end, of a claw-hammer provided with an orifice adapted to frictionally engage with the tip end of the pinch-bar, means for securing the claw-hammer to the tip end of the pinch-bar, and the claw-hammer having 20 a reduced end designed to be inserted in the socket, as and for the purpose specified.

In witness whereof I have hereunto set my hand in the presence of two witnesses.

DANIEL McCHESNIE.

Witnesses:

RHEA KAUPP,
FRANK SMITH.
